ATTORNEY.

UNITED STATES PATENT OFFICE.

JOSHUA R. RITCHIE, OF PHILADELPHIA, PENNSYLVANIA.

DESIGN FOR A PICTURE OR MIRROR FRAME.

SPECIFICATION forming part of Design No. 11,835, dated June 29, 1880.

Application filed April 27, 1880. Term of patent 3½ years.

To all whom it may concern:

Be it known that I, JOSHUA R. RITCHIE, a citizen of the United States, residing in the city and county of Philadelphia, and State of Pennsylvania, have invented and produced a new and original Design for a Picture or Mirror Frame, of which the following is a specification, reference being had to the accompanying photographic illustration, forming part 10 thereof.

My invention consists of a design for frames adapted for pictures, mirrors, and other purposes.

15 A represents a frame, which is in the form of a horseshoe, with nail-heads a. B represents a bracket, which is connected to the frame and projects forward from the base thereof.

The frame presents a neat, tasty, and suggestive design.

The bracket may be ornamented with fringe, 20 as shown, this, however, not being an important feature of the design.

What I claim is—

A design for a picture or mirror frame of the form of a horseshoe, having the bracket B 25 projecting forward from the base thereof, as described, and shown in the accompanying photographic illustration.

JOSHUA R. RITCHIE.
